2,016,371

TREATMENT OF HYDROCARBON OILS

Lyman C. Huff, Chicago, Ill., assignor to Universal Oil Products Company, Chicago, Ill., a corporation of South Dakota

Application March 30, 1931, Serial No. 526,239

2 Claims. (Cl. 196—49)

This invention relates to the treatment of hydrocarbon oils, and particularly refers to an improved process and apparatus for the conversion of hydrocarbon oils in combination with which is operated a process for separating relatively light components from crude oil.

The primary concepts of the invention provide an improved process for the conversion of relatively heavy oils into more desirable lower boiling products, heat recovered from the gaseous and liquid products of the conversion being utilized in the distillation of crude oil for the purpose of removing the naturally-contained relatively light fractions thereof.

15 A more specific embodiment of the invention may comprise supplying raw oil charging stock to one or a plurality of heating elements, introducing the heated oil into an enlarged reaction zone, withdrawing liquid and vaporous products from 20 said reaction zone to a vaporizing zone preferably maintained under reduced pressure; withdrawing residual liquid from said vaporizing zone, subjecting vapors from said vaporizing zone to fractionation, returning reflux condensate from 25 the fractionator to the aforementioned heating zone or zones for further conversion; subjecting the desirable light components of the fractionated vapors to condensation and cooling and collecting resulting products, passing a crude oil in indirect 30 heat exchange relation with the relatively hot cracked vapors and in indirect heat exchange relation with the relatively hot residual oil from the cracking system and thence supplying the heated crude to a topping system wherein the relatively 35 light components thereof may be vaporized, the vapors subjected to fractionation and their desirable light components condensed and collected.

As a special feature of the present invention the heating zone of the cracking system may comprise 40 a plurality of separate furnaces and heating elements of any desired form, the oil to be treated preferably being supplied in part to each of the heating elements simultaneously and the streams of heated oil commingling and passing into the reaction chamber. Substantially the same conversion 45 conditions are preferably maintained in each heating element.

The attached diagrammatic drawing will serve to more clearly illustrate the principles and features of the invention.

The raw oil charging stock to be cracked may be supplied through line 1 and valve 2 to pump 3 from which it may be supplied through line 4, line 5 and valve 6 to fractionator 55 7, wherein it may be preheated by contact

with the relatively hot vapors in this zone and may pass together with the insufficiently converted components of the vapors which may be condensed in the zone through line 8 and valve 9 to pump 10. Pump 10 may supply the reflux condensate from fractionator 7, alone or together with preheated raw oil as the case may be, through line 11 and valves 12 and 13 to the heating zone of the system. A portion or all of the raw oil may, instead of passing overhead to fractionator 7, 10 pass directly through valve 14 in line 4 into line 11 and thence through valve 13 to the heating zone together with the oil supplied from pump 10 as already described.

The heating zone which is here illustrated comprises two separate heating elements 15 and 16 located respectively in suitable furnaces 17 and 18. Substantial equal amounts of oil are preferably supplied simultaneously to each of the heating elements from line 11 through lines 19 and 20 controlled respectively by valves 21 and 22. The divided streams of oil are preferably subjected to substantially the same conversion conditions in each heating element and may be discharged through lines 23 and 24 controlled respectively by 25 valves 25 and 26 into line 27, wherein the two streams may be commingled and may pass to reaction chamber 28. Preferably a substantially superatmospheric pressure is employed in the heating zone and in the reaction chamber. The 30 pressure employed in the reaction chamber may, if desired, be lower than that employed in the heating zone. Preferably the pressures employed in the two heating elements are substantially the same.

35 Preferably both vaporous and liquid products are withdrawn from chamber 28 through line 29 and valve 30 to vaporizing chamber 31, wherein the vapors and residual oil may be separated. The residual liquid may be withdrawn from the 40 system to cooling, and storage or any desired further treatment through line 32 and valve 33, heat exchanger 34 and line 35. Vapors may pass from chamber 31 through line 36, valve 37, heat exchangers 38 and 39 and line 40 to fractionator 7, 45 from which reflux condensate may be returned, as already described, for reconversion. A portion of the vapors and gases from chamber 28 may, if desired, be withdrawn through line 57 and valve 58 and may be introduced into the lower 50 portion of fractionator 7 in direct contact with the reflux condensate accumulated therein to reboil this product and substantially free it of entrained desirable light materials. The relatively light desirable components of the vapors 55

subjected to fractionation may be withdrawn from the fractionator through line 41 and valve 42, may be passed through heat exchanger 43 to be subjected to condensation and cooling in condenser 44, products from which may pass through line 45 and valve 46 to be collected in receiver 47. Uncondensable gas may be released from the receiver through line 48 and valve 49. Distillate may be withdrawn through line 50 and valve 51. A portion of the distillate may, if desired, be withdrawn from receiver 47 through line 52 and valve 53 and may be recirculated by means of pump 54 through line 55 and valve 56 to the upper portion of fractionator 7 to assist fractionation of the vapors in this zone.

A crude oil containing a substantial proportion of light components such as gasoline may be supplied through line 60 and valve 61 to pump 62, from which it may be fed through line 63 and valve 64 to heat exchanger 43 where it may be preheated by indirect contact with vapors from fractionator 7. The crude oil may thence pass through line 65 to heat exchanger 34 where it may be further preheated by indirect heat exchange relation with residual oil withdrawn from chamber 31 and from which it may pass through line 66 to heat exchanger 39. Heat exchanger 39 may be located in the path of vapors passing from chamber 31 to fractionator 7 and the crude oil supplied therethrough may receive additional heat by indirect contact with these vapors passing therefrom through line 67 and valve 68 into the topping zone or fractionator 69.

It will be understood that any or all the heat exchangers mentioned may be utilized for the purpose of preheating the crude oil and if desired additional heat may be supplied to the crude from the cracking system or from any external source not illustrated in the drawing. The crude oil is preferably heated sufficiently to effect vaporization of a substantial portion of the oil including the light components which are to be separated. The vapors may be subjected to fractionation in column 69 to effect final separation of the desirable light components of the crude which may pass through line 70 and valve 71, may be subjected to condensation and cooling in condenser 72, products from which may pass through line 73 and valve 74 to be collected in receiver 75. If desired, side streams of somewhat higher boiling products may be withdrawn from the fractionator, for example, through line 87 and valve 88, to be separately cooled and collected. Uncondensable gas may be released from the receiver 75 through line 76 and valve 77. The distillate may be withdrawn through line 78 and valve 79. A portion of the distillate may be, if desired, withdrawn from receiver 75 through line 80 and valve 81 and may be recirculated by means of pump 82 through line 83 and valve 84 to the upper portion of fractionator 69 to assist in maintaining the desired outlet temperature and to assist in maintaining the desired degree of fractionation in this zone. The topped crude oil, that is, that portion of the crude remaining unvaporized or condensed in fractionator 69, may be withdrawn from the fractionator through line 85 and valve 86 to cooling and storage or to any desired further treatment. If desired, a portion or all of this oil may comprise a portion or all of the charging stock supplied to the cracking process and may be introduced into line 1 through line 89 and valve 90, passing thence to pump 3 to be supplied therefrom to the cracking system 75 as already described.

Pressures employed in the cracking system may range from atmospheric to superatmospheric pressures as high as 2000 pounds per square inch or more, the preferred range being between 100 and 1000 pounds per square inch. Substantially equalized pressures may be employed throughout the cracking system or differential pressures may be utilized between any of the various elements. Preferably a substantial reduced pressure is employed in the vaporizing chamber and in succeeding fractionating, condensing and collecting equipment of the cracking system relative to that employed in the conversion zone. Conversion temperatures employed may range from 800 to 1200° F. more or less. The preferred temperatures range between 850 to 900° F. The specific conditions chosen depend on the charging stocks and the results desired. The topping system may be operated under substantial atmospheric, subatmospheric or 20 superatmospheric pressures.

As a specific example of operating conditions which may be employed in the practice of the present invention and results which may be obtained therefrom, a crude oil containing approximately 30% of material coming within the boiling range of motor fuel is heated to a temperature of approximately 550° F. by heat recovered from the cracking system and the evolved vapors are subjected to fractionation under substantially atmospheric pressure. A temperature of about 425° F. is maintained at the top of this fractionating zone and the straight run gasoline is condensed and collected. Topped crude meeting market specifications for bunker "A" fuel oil is withdrawn from the fractionator or topping zone. The charging stock supplied to the cracking system consists of a blend of approximately 75% topped crude from the topping operation previously described, about 15% of a relatively low grade crude oil containing substantially no motor fuel and about 10% of pressure distillate bottoms from another cracking operation. This oil is subjected in the two heating elements to a temperature of about 930° F. under a superatmospheric pressure of about 300 pounds per square inch. Substantially the same pressure is utilized in the reaction chamber but is reduced in the vaporizing chamber and succeeding portions of the cracking system to approximately 35 pounds per square inch. This operation may yield approximately 60% of gasoline based upon the topped crude oil having an anti-knock value approximately equivalent to a blend of 60% benzol and 40% straight run Pennsylvania gasoline. In addition, about 30% of good quality fuel oil is produced by the cracking operation, the remaining products being uncondensable gas and a relatively small percentage of coke or carbonaceous material.

I claim as my invention:

1. A hydrocarbon oil conversion process which comprises subjecting the oil to cracking conditions of temperature and pressure in a cracking zone and separating the same into vapors and unvaporized oil, passing crude oil in indirect heat exchange relation with vapors from the separating step and heating the crude to the vaporizing temperature of lighter fractions thereof, releasing such lighter fractions from the crude in a vaporizing zone and condensing and collecting the same, flash distilling the unvaporized oil by pressure reduction and combining resultant flashed vapors with the first-mentioned vapors, dephlegmating the commingled vapors in direct

contact with unvaporized portions of the crude in a fractionating zone independent of said vaporizing zone, supplying the resultant mixture of reflux condensate and unvaporized crude oil 5 to the cracking zone, and finally condensing the dephlegmated vapors independently of the vapors of said lighter fractions of the crude.

2. A conversion process which comprises subjecting hydrocarbon oil to cracking conditions 10 of temperature and pressure in a cracking zone and separating the same into vapors and residue in a separating zone maintained under lower pressure than the cracking zone, passing crude oil in indirect heat exchange relation with heated 15 products from the separating zone and heating the crude to the vaporizing temperature of lighter fractions thereof, discharging the heated crude into a vaporizing zone apart from the sep-

arating zone and releasing the lighter fractions thereof as vapor in this zone, removing such separated crude oil vapors from the vaporizing zone and condensing and collecting the same, passing vapors from the separating zone into a fractionating zone independent of said vaporizing zone, removing unvaporized portions of the crude from the vaporizing zone and introducing the same into said fractionating zone, dephlegmating the vapors in the fractionating zone in contact with 10 said unvaporized portions of the crude and supplying the resultant mixture of reflux condensate and unvaporized crude oil to the cracking zone, and finally condensing the dephlegmated vapors independently of said separated crude oil va- 15 pors removed from said vaporizing zone.
